UNITED STATES PATENT OFFICE

ERNEST JAMES SMITH, OF LONDON, ENGLAND, ASSIGNOR TO GOSS PRINTING PRESS COMPANY, OF CHICAGO, ILLINOIS, A CORPORATION OF ILLINOIS

PRINTING PRESS

Application filed January 23, 1930. Serial No. 422,905.

My invention relates to printing presses and has for its object the provision of a new and improved form and arrangement of parts by the use of which distinctive markings may be made on the outside faces of critical papers or sections in the run of the press whereby such marked papers shall define the limits of successive equal-sized bundles or piles of papers or sections.

10 It is one of the objects of my invention to provide a construction by which adjustment may be readily effected for varying the number of the papers or sections in successive indicated bundles or for varying the action of 15 the printing and controlling mechanism for keeping the number of the papers in the successive indicated bundles constant when a shift is made from straight run to collection run or vice versa.

20 It is one of the objects of my invention to improve mechanisms of this type in sundry details hereinafter specified. The preferred means by which I have accomplished my several objects are illustrated in the accompanying drawings and are hereinafter specifically described. That which I believe to be new and desire to cover by Letters Patent is set forth in the claims.

In the drawings,—

30 Fig. 1 is a side view of a press comprising my improved construction, only one of the unit sections of the press being illustrated together with the folding mechanism, a press of this type ordinarily being provided with 35 two or three unit sections at each side of the centrally located folding mechanism;

Fig. 2 is a fragmentary view of the parts looking toward the left at the line 2—2 of Fig. 1;

40 Fig. 3 is a top plan view of my improved construction, the major portion of the structure as shown in said Fig. 3 being omitted from Figs. 1 and 2 which are shown diagrammatically upon a smaller scale;

45 Fig. 4 is a vertical cross section taken on line 4—4 of Fig. 3;

Fig. 5 is an end view of the parts shown in Fig. 4 as seen from the right therein; and

50 Figs. 6 and 7 are views of portions of the parts as shown in Fig. 5 but with substitute

gearing employed for changing the number of papers or sections in the unit pile or bundle.

Referring now to the several figures of the drawings, in which corresponding parts are indicated by the same reference characters, 10 indicates a bed plate, having frame members or standards 11 and 12 rising therefrom in spaced relation to each other, each of the standards 11 and 12 being preferably formed in sections in the ordinary manner. Each of the unit sections of the press is provided with form cylinders 13, and impression cylinders 14, together with suitable inking mechanisms for printing a web 15 on both faces thereof, means being provided at the top of the section for cutting the web 15 into two parts and for superposing one of such web parts on the other, such two web portions being indicated by the numerals 16 and 17. In Fig. 1, I have also indicated two additional webs 18 and 19 which have been printed by the press section next to the right of the press section illustrated, and have shown also webs 20, 21, 22 and 23 coming from the press sections at the right of the folder mechanism shown, the webs 20, 21, 22 and 23 being shown in dotted lines for indicating their optional use as may be desired.

In the arrangement as illustrated in Fig. 1 in solid lines, the webs 17, 18 and 19 are shown as passing under rollers 24, 25 and 26, while the web 16 is fed over the roller 27, all of the webs being brought together over a roller 28 at the upper edge of the former structure indicated in Fig. 1 by the numeral 29. A second former 30 is also provided directly opposite the former 29 for use if desired for producing a folded product independently of that passing over the former 29. It will be understood, of course, that if desired the webs 16, 17, 18 and 19 might be handled over one of the formers and the webs 20, 21, 22 and 23 handled over the other former. It will be understood also that in case all eight of the webs were run over a single one of the two formers, in such case the web 16 would be shifted to pass under the roller 31 instead of over the roller 27, in such case the web 20

80

85

90

95

100

100

being passed over the roller 27 in lieu of the web 16.

In Figs. 3 to 7, in which my improved construction is shown in detail, the roller 27 there shown is the roller over which the web 16 or the web 20 is passed just before reaching the former as above described.

This roller 27 is provided with a gear 32 on the end of its shaft adjacent to the standard 11, by which gear 32 the roller 27 is to be driven at the same surface speed as that of the webs. In the construction shown, the circumference of the roller 27 is just half the size of the sheet longitudinally of the web as cut by the cutting and folding mechanism, with the result that the margins of successive pages passing over the roller come always at the same point circumferentially of the roller.

For supporting auxiliary printing means movably in position for operation upon the uppermost web passing to the former 29 or 30, I have provided a rock shaft 33 revolvably mounted in the standards 11 and 12, being provided with arms 34 extending therefrom, between the ends of which are mounted two short shafts 35. Each of the shafts 35 is driven at the same angular speed as that of the roller 27 by means of intermeshing gears 36 and 37 mounted upon the shafts 35 and the roller 27, as is clearly shown in Fig. 4. Upon the inner end of each of the shafts 35, I have provided a head 38 equipped with a suitable printing plate 39 adapted when in operative position to print a distinctive marking of any approved form upon the web passing over the roller 27, the roller 27 being provided with impression rings 40 for suitable cooperation with the printing plate. For inking the plate 39, I have provided a felt roller 41 supported by a bracket 42 above the head 38 in position to permit the plate 39 to engage the roller 41 upon each complete revolution of the shaft 35 and the parts carried thereby. The head 38 is of such size as to cause the face of the plate 39 to have the same surface speed as that of the roller 27 and the web 16.

Means is provided for rocking the rock shaft 33 in timed relation to the rotation of the roller 27 for holding the printing plate 39 out of operative relation to the roller 27 during the greater portion of the time but permitting such auxiliary printing mechanism to descend into operative position as shown in Fig. 4 at timed intervals for printing a distinctive marking upon the outer face of the front page of certain predetermined papers or sections separated from each other by a predetermined number of intervening papers or sections. This means comprises a worm 43 carried by the shaft of the roller 27, with which worm meshes a worm gear 44 mounted on the upper end of a vertically disposed shaft 45. This shaft 45 is connected with a hori-

zontally extending shaft 46 by means of beveled gears 47 and 48, the outer end of the shaft 46 being provided with a pinion 49. In the construction shown, the beveled gears 47 and 48 are of equal size, and the worm gearing has a ratio of 25 to 1, with the result that the pinion 49 is given a single rotation for each twenty-five rotations of the roller 27.

Adjacent to the pinion 49 on the outer face of the standard 12, I have revolvably mounted a gear 50 which is fixedly connected with a cam disc 51. The pinion 49 is operatively connected with the gear 50 by means of an idler gear 52 which is revolvably mounted upon a swingingly mounted arm or lever 53 so as to mesh with both the pinion 49 and said gear 50, the gear 52 being of just one-half the size of the gear 50, and four times as large as the pinion 49. With this construction, it will be appreciated that the cam disc 51 is given a complete rotation for every two hundred rotations of the roller 27, being a single complete rotation for every one hundred sheet lengths of web passing over the roller 27.

As is best shown in Fig. 7, the disc 51 is provided with a notch 54 at one point in its periphery, adapted to be engaged by a roller 55 carried by an arm 56 fixed upon the end of the rock shaft 33. The arrangement is such that when the roller 55 engages the outer periphery of the cam disc 51, each of the shafts 35 is held in slightly elevated position so that the printing plate 39 is revolved past the roller 27 without being brought into contact with the web passing over the roller. The arrangement is such, however, that when the roller 55 drops into the notch 54 of the cam disc, the rock shaft 33 is given a slight movement in counter-clockwise direction in Fig. 5 for bringing the arms 34 downwardly momentarily for permitting the printing plate 39 to have operative engagement with the web passing over the roller 27. The size of the notch 54 is such that the shaft 33 is held in its turned position only long enough for permitting a single operative engagement of the printing plate 39 with the web. The arrangement is such that the gears 36 and 37 remain in mesh with each other when the shafts 35 are raised, with the result that the auxiliary printing mechanism is rotated both during the time when it is operative and when it is inoperative.

By the arrangement just described, in which the auxiliary printing mechanism is lowered into operative position once during each 200 revolutions of the roller 27, it is apparent that each one hundredth paper or section is given a distinctive marking when the press is operated upon a straight run basis. When, however, the press is operating upon a collect basis, the 100 lengths of web passing over the roller 27 during such 200 revolutions of said roller are, of course, folded into 50 120

papers or sections, so that in such case every fiftieth paper or section has the distinctive marking showing upon the front page.

In Fig. 6, I have illustrated a construction which is exactly similar to that shown in the figures above described, except that in Fig. 6 a gear or pinion 57 is substituted upon the horizontally extending shaft 46 in place of the pinion 49. For accomplishing this result, the arm or lever 53 is moved downwardly and secured in position for proper meshing of the gear 52 with the substituted gear or pinion 57. In the construction shown, the gear or pinion 57 is just twice as large as the pinion 49, and just one-half the size of the gear 52. With the gear or pinion 57 in use upon the shaft 46, the cam disc 51 is given a single revolution for each 100 revolutions of the roller 27. Upon this basis, the roller 55 carried by the arm or lever 56 is permitted to engage the notch 54 of the cam disc 51 just once for each fifty page lengths passing over the roller 27. That is to say, with the gear or pinion 57 in use, a distinctive marking is made upon each fiftieth paper or section when the press is operated upon the straight run basis; when the press is running upon a collect basis with the gear or pinion 57 in use, the distinctive marking is seen upon the front page of each twenty-fifth paper or section.

In Fig. 7, a gear 58 is substituted in lieu of the gear or pinion 57 upon the horizontally extending shaft 46, such gear 58 being of the same size as the gear 52, the substitution of the larger gear 58 being permitted by reason of the downward adjustment of the arm or lever 53. With the gear 58 in use, the cam disc 51 is given a single rotation for each 50 rotations of the roller 27. Upon this basis, when the press is being operated upon a straight run basis, each twenty-fifth paper or section would show the distinctive marking upon its front face.

By the use of the mechanism as above described, I am enabled to divide the papers or sections coming from the folding mechanism of the press into indicated bundles of either 25 sections or papers, 50 sections or papers, or 100 sections or papers. I am enabled to divide the papers or sections into either 25 or 50 section bundles either when the press is running upon a straight run basis or upon a collect basis. As will be very readily understood, if it were desired to divide the product of the press into bundles of any other predetermined number of units, this result could be obtained by the substitution of still other gears or pinions in lieu of the gears 57 and 58.

While I prefer to employ the construction as illustrated in the drawings and as above described, it is to be understood that my invention is not to be limited to the precise form of mechanism as shown and described, except so far as it may be so limited by the

prior art, it being understood that changes might well be made in the construction without departing from the spirit of my invention.

I claim:

1. In a printing press mechanism, the combination of means for printing and folding a plurality of pages into a unit product, auxiliary printing means for printing a distinctive marking on the outside face of a unit, a swingingly mounted arm upon which said auxiliary printing means is mounted, a gear carried by said arm and meshing with a gear on the press for driving said auxiliary printing means and adapted to remain in mesh when the arm is swung, and cam means driven in fixed speed relation to the press adapted to give said arm a swinging movement for moving said auxiliary printing means into and out of printing position and causing it to print on only certain units separated from each other in the run of the press by a predetermined number of intervening units.

2. In a web printing press mechanism, the combination of means for printing and folding a plurality of pages into a unit product, a roller engaging the web forming the outside faces of the unit product, a rock shaft adjacent to said roller, rotary printing means movably mounted adjacent to said roller and adapted to be moved into and out of printing relationship with the web passing over said roller by slight rotary movements of said rock shaft, means for rotating said movably mounted printing means in timed relation to the press, and means for rocking said rock shaft at timed intervals for moving said printing means momentarily into printing relationship with the web for printing distinctive markings on only certain units separated from each other in the run of the press by a predetermined number of intervening units.

3. In a web printing press mechanism, the combination of means for printing and folding a plurality of pages into a unit product, a roller engaging the web forming the outside faces of the unit product, a rock shaft adjacent to said roller, arms extending outwardly from said rock shaft, a short shaft revolvably mounted on said arms opposite said roller, printing means carried by said last named shaft, means for giving said rock shaft slight rotary movements at timed intervals for moving said printing means momentarily into printing relationship with the web passing over said roller for printing distinctive markings on only certain units separated from each other in the run of the press by a predetermined number of intervening units, and means for rotating said short shaft from said roller for continuously driving the printing means at substantially the surface speed of the web.

4. In a web printing press mechanism, the combination of means for printing and fold-

ing a plurality of pages into a unit product, a roller engaging the web forming the outside faces of the unit product, a rock shaft adjacent to said roller, arms extending outwardly from said rock shaft, a short shaft revolubly mounted on said arms opposite said roller, printing means carried by said last named shaft, means for giving said rock shaft slight rotary movements at timed intervals for moving said printing means momentarily into printing relationship with the web passing over said roller for printing distinctive markings on only certain units separated from each other in the run of the press by a predetermined number of intervening units, and intermeshing gears carried by said roller and said short shaft for continuously driving the printing means at substantially the surface speed of the web both when the printing means is in operative printing relationship to the web and when it is moved out of operative position.

5. In a web printing press mechanism, the combination of means for printing and folding a plurality of pages into a unit product, a roller engaging the web forming the outside faces of the unit product, means for driving said roller at the same surface speed as that of the web, auxiliary printing means adapted to cooperate with said roller for printing a distinctive marking on the outside face of a unit, a cam for moving said printing means toward and from said roller at timed intervals for printing distinctive markings on only certain units separated from each other in the run of the press by a predetermined number of intervening units, and positively acting driving connections between said roller and said cam adjustable for controlling the timing of the action of said printing means for regulating the number of units intervening between those upon which said auxiliary printing means acts.

6. In a web printing press mechanism, the combination of means for printing and folding a plurality of pages into a unit product, a roller engaging the web forming the outside faces of the unit product, means for driving said roller at the same surface speed as that of the web, auxiliary printing means adapted to cooperate with said roller for printing a distinctive marking on the outside face of a unit, a cam for moving said printing means toward and from said roller at timed intervals for printing distinctive markings on only certain units separated from each other in the run of the press by a predetermined number of intervening units, a gear rotatable with said cam for driving the same, a second gear meshing with said first named gear in any adjusted position thereabout, and other gearing for driving said second gear from said roller.

7. In a web printing press mechanism, the combination of means for printing and fold-

ing a plurality of pages into a unit product, a roller engaging the web forming the outside faces of the unit product, means for driving said roller at the same surface speed as that of the web, auxiliary printing means adapted to cooperate with said roller for printing a distinctive marking on the outside face of a unit, a cam for moving said printing means toward and from said roller at timed intervals for printing distinctive markings on only certain units separated from each other in the run of the press by a predetermined number of intervening units, a gear rotatable with said cam for driving the same, an arm mounted to swing about the axis of said gear, a second gear mounted on said arm and meshing with said first named gear, and variable speed gearing meshing with said second gear and connected with said roller.
